STEEL TAPE HOLDER

Carl A. Brown, Aberdeen, Md.

Application February 13, 1945, Serial No. 577,717

3 Claims. (Cl. 33—137)

(Granted under the act of March 3, 1883, as amended April 30, 1928; 370 O. G. 757)

1

The invention described herein may be manufactured and used by or for the Government for governmental purposes without the payment to me of any royalty thereon.

This invention relates to a tool or implement for holding an end of a flexible measuring tape.

In star gauging gun barrels a flexible tape, placed under a predetermined tension, is ordinarily used for measuring the length of the gun barrel being gauged. As many gun barrels are equipped with flash hiders, it is necessary to remove the flash hider in order to accurately adjust and position the tape relatively to the muzzle of the barrel. The removal of the flash hider and its reapplication to the barrel, after the measurements have been made, require considerable time.

It is therefore a primary aim of this invention to provide an implement capable of quickly anchoring an end of a flexible tape to accurately position a desired graduation of the tape at the muzzle end of a gun barrel, equipped with a flash hider, without removal of the flash hider, to thereby expedite the operation of measuring the gun barrel.

Still a further aim of the invention is to provide an implement capable of being utilized for accurately positioning a desired graduation of a flexible measuring tape in alignment with the muzzle end of a gun barrel, irrespective of whether or not said barrel is equipped with a flash hider, to thus provide mechanical means for accurately holding the anchored end of a tensioned measuring tape in a desired position.

Other objects and advantages of the invention will hereinafter become more fully apparent from the following description of the drawing, which illustrates a preferred embodiment of the invention, and wherein:

Figure 1 is a top plan view, partly in section, showing the tape holder in an applied position;

Figure 2 is a side elevational view, partly in section, of the same;

Figure 3 is a perspective view of the tape holder; and

Figure 4 is a cross sectional view, on a reduced scale, of the tape holder in an applied position, taken substantially along the plane of the line 4—4 of Figure 1.

Referring more particularly to the drawing, wherein like reference characters designate like or corresponding parts, throughout the different views, 5 designates the muzzle end of a gun barrel to which is detachably connected a flash hider 6. These parts are of conventional construction and form no part of this invention, but are illustrated

2

and described merely to better illustrate the use of the tape holder designated generally 7 and comprising the invention.

Tape holder 7 includes an elongated shank 8 having an enlarged head 9 which is suitably secured to or formed integral with one end thereof. Head 9 is transversely disposed relatively to the longitudinal axis of the shank 8 and is provided with a substantially flat outer side 10 for purpose which will hereinafter become apparent. Head 9 is provided with a relatively wide opening 11 which is disposed above the shank 8. The shank 8, adjacent the end thereof provided with the head 9, is provided with an integral hook 12 which opens away from the head 9. The opposite end 13 of the shank 8 forms the handle of the implement 7 and may be of any length, size or shape.

Referring to Figs. 1 and 2, 14 designates an end of a conventional flexible measuring tape which may be formed of steel or any other suitable material which is non-elastic and which, as seen in Fig. 1, is graduated in inches. A link or loop 15 is attached to one end of the measuring tape 14.

In star gauging a gun barrel, the length of the gun barrel is generally measured by a flexible steel tape which extends therethrough and which is placed under a uniform pull at the breach end of the barrel. The tape is suitably held at its opposite end so that the zero graduation thereof is flush with the muzzle end of the barrel. In order to accomplish this result, when the barrel is equipped with a flash hider, it has in the past been necessary to remove the flash hider so as to expose the muzzle of the barrel to correctly position the tape relative thereto.

By the use of the tape holder 7, the operation of removing and replacing the flash hider 6 eliminated. To measure the length of the barrel 5, while equipped with a flash hider 6, the measuring tape 14 is extended therethrough and the loop end 15 thereof is passed through the opening 11 in a direction from the outer side 10 of the head and toward the hook 12. The loop 15 is then engaged over the hook 12 and when positioned in the recess 16 thereof, as illustrated in Figs. 1 and 2, and the tape 14 is pulled taut, the zero graduation of the tape 14, as seen in Fig. 1, is flush with the side or face 10. Thus, by positioning the headed end of the implement 7 in the flash hider 6 and with the face 10 bearing flush against the muzzle end of the barrel 5, the zero graduation of the tape 14 will be accurately positioned in alignment with the muzzle end of the barrel, so that the length of the barrel can be accurately measured. Thus, the imple-

ment 7 eliminates the additional labor required to remove and replace the flash hider 6 in order to measure the barrel 5, and in addition provides an accurate means for anchoring or holding the tape in the desired position relatively to the barrel muzzle. The head 9 is of sufficient size so that it will fit readily into the flash hider 6 and yet bear against the muzzle end of the barrel 5. Obviously, the size of the head 9 can be varied depending upon the caliber of the barrel 5 with which it is to be used. The recess 16 is disposed at substantially the same level as the opening 11 so that the tape 14 will be substantially flat and level on both sides of the opening 11, through which it loosely extends.

Various modifications and changes in the invention, as illustrated and described, are contemplated and may obviously be resorted to without departing from the spirit and scope of the invention as hereinafter defined by the appended claims.

I claim:

1. A tape holder for use in measuring weapon barrels, comprising an elongated shank forming a handle, a head formed on one end of the shank, said shank having a hook opening away from the head, and said head being provided with an opening for loosely engaging a portion of a measuring tape, one end of the tape being detachably connected to the hook.
2. A tape holder for use in measuring weapon barrels, comprising a head having an elongated opening therein for receiving an end of a measuring tape, a shank formed integral with and projecting from one side of the head and away from the other end of the tape, the headed end of the holder being adapted to be positioned with

5 in a flash holder and with the opposite side of the head bearing against the muzzle end of a barrel to which the flash holder is connected, and means comprising a hook to which one end of the tape is detachably connected formed on said shank and opening away from the head for engaging a loop on the first mentioned end of the tape, for positioning the zero graduation of the tape flush with the last mentioned side of the head and with the muzzle end of the barrel.

in a flash holder and with the opposite side of the head bearing against the muzzle end of a barrel to which the flash holder is connected, and means comprising a hook to which one end of the tape is detachably connected formed on said shank and opening away from the head for engaging a loop on the first mentioned end of the tape, for positioning the zero graduation of the tape flush with the last mentioned side of the head and with the muzzle end of the barrel.

3. A measuring tape holder comprising a head having an elongated opening therein for loosely engaging an end portion of a tape, a shank formed integral therewith and projecting from one side of the head and away from the other end of said tape, the other side of the said head being adapted to engage a portion of the object to be measured, a projection on said shank forming a handle, and a hook formed on said shank opening away from the head for detachably engaging a loop on the first mentioned end of the tape for positioning zero graduation of the tape flush with the last mentioned side of the head, the recess in said hook being disposed at substantially the same level as the elongated opening, whereby the said tape will be substantially flat and level on both sides of the said opening.
